[57] CLAIM

The ornamental design for a distiller, as shown and described.

DESCRIPTION

FIG. 1 is a perspective view of a distiller constructed in accordance with one preferred embodiment of the invention; FIG. 2 is an elevation view of the front of the distiller shown in FIG. 1;

FIG. 3 is an elevation view of the rear of the distiller shown in FIGS. 1 and 2;

FIG. 4 is an elevation view of the right side of the distiller shown in FIGS. 1-3;

FIG. 5 is an elevation view of the left side of the distiller shown in FIGS. 1-4;

FIG. 6 is a top plan view of the distiller shown in FIGS. 1-5; and,

FIG. 7 is a bottom plan view of the distiller shown in FIGS. 1-6.

The broken lines on portions of the distiller are for the purpose of illustrating unclaimed environmental structure only.
